No. 820,171.

PATENTED MAY 8, 1906.

J. W. BARNES.

FENCE POST.

APPLICATION FILED AUG. 28, 1905.

UNITED STATES PATENT OFFICE.

JOHN W. BARNES, OF MOUNT GILEAD, OHIO.

FENCE-POST.

No. 820,171.

Specification of Letters Patent.

Patented May 8, 1906.

Application filed August 28, 1905. Serial No. 275,412.

To all whom it may concern:

Be it known that I, JOHN W. BARNES, a citizen of the United States, residing at Mount Gilead, in the county of Morrow and State of Ohio, have invented a new and useful Fence-Post, of which the following is a specification.

This invention relates to fence-posts, and has for its object to form the same from a metal blank which may be conveniently folded to complete the post in a simple and inexpensive manner, it being particularly designed to adapt the post for the support of wire fencing.

Another object of the invention is to produce from the blank an anchor capable of effectually supporting the post in an upright position without the employment of any extraneous anchoring or bracing means.

A still further object of the invention is to adapt the same for use as an end post as well as an intermediate post.

It is furthermore designed to enable the convenient attachment of runner-wires to the post in a simple and effective manner and to provide for taking up slack in the runner-wires through the medium of the means for fastening the wires to the post.

With these and other objects in view the present invention consists in the combination and arrangement of parts, as will be herein-after more fully described; shown in the accompanying drawings, and particularly pointed out in the appended claims, it being understood that changes in the form, proportion, size, and minor details may be made within the scope of the claims without departing from the spirit or sacrificing any of the advantages of the invention.

In the accompanying drawings, Figure 1 is a perspective view of an end post and an intermediate post of the present invention supporting a wire fence made up of runner-wires. Fig. 2 is a view of the blank from which the post is made. Fig. 3 is a cross-sectional view of an intermediate post. Fig. 4 is a top plan view of an end post.

Like characters of reference designate corresponding parts in each and every figure of the drawings.

The blank from which the post of the present invention is formed is designated 1 and shown in Fig. 2 in its condition prior to being bent to complete the post. This blank is substantially oblong in form and has its longitudinal edges parallel, as at 2, for a rela-

tively short distance, and then the longitudinal edges are converged slightly toward the other end of the blank. That end of the blank which has the parallel edges is provided with a longitudinal slit or cleft 3 midway between the parallel edges and equal in length to one of said edges. This slit divides the adjacent end portion of the blank into what will be termed "base" members 4 and 5, the member 4 being provided with a pair of perforations 6, located adjacent its side edge at the corners thereof, while the section 5 is provided with a pair of perforations 7 adjacent the outer edge of the member and in the corners thereof. The converged edges of the blank are provided with a series of transverse slots or notches 8, each of which terminates at its inner end with a transverse enlargement 9, extending at opposite sides of the notch. Located midway between corresponding notches is a series of perforations 10. The blank thus described is folded along its longitudinal center, so as to produce an angle-post, having its sides 11 and 12 disposed at substantially right angles to one another with the fold or corner extending through the series of perforations 10. In folding the blank one of the base-sections overlaps the other and has its inner edge engaged with the opposite side of the post, as clearly indicated in Fig. 1, after which rivets 13 are passed through the openings 6 and 7, which come into alignment when the base members are folded. The post is now complete and ready to be set up with its lower portion embedded in the ground, the composite base made up of the members 4 and 5 constituting an anchor to support the post in an upright position without the employment of extraneous anchoring and bracing means.

When the post has been set up, the fence-wires 14 are passed through corresponding notches 8 and into the seats 9, whereby the wires are conveniently assembled with the post.

To prevent the displacement of the wires from the seats of the post, hooks or eyebolts 15 are engaged with the respective wires and passed through certain of the perforations 10, a nut 16 being fitted upon the threaded extremity of each hook or eyebolt and set up tight against the back of the post. It will of course be understood that the nuts are employed to draw the hooks or fasteners rearwardly, so as to kink the wires across the

seats, and thereby hold the wires against endwise looseness. Should any slack occur in the wires, it may be taken up by tightening the nuts. By the provision of a series 5 of perforations 10 between each pair of seats 9 the fastening 15 may be adjusted to such a height as is required by the adjacent runner-wire, thereby to enable the convenient engagement of the hook or eyebolt with the 10 wire and to accommodate the fastening with respect to the height of the wire within the seats.

To produce an end post, as shown in Figs. 1 and 4, four of the intermediate posts are 15 assembled back to back and then fastened by means of rivets 17, passed through the contiguous sides of adjacent post members. When forming an end post of this character the edge notches and seats 8 and 9 are omitted, and the contiguous sides of one pair of post members are pierced by a series of openings 19, through which the runner-wires are 20 passed, and then fastened in any suitable manner—such, for instance, as being twisted 25 upon themselves, as clearly indicated in the drawings.

Having fully described the invention, what is claimed is—

1. A fence-post formed of plate metal 30 which is bent longitudinally to produce an angle-post, the bottoms of the sides of the post being bent at substantially right angles thereto and overlapped to form an anchoring-base, the longitudinal edges of the post 35 being provided with angle-notches, the back

of the post being provided with perforations between notches, hooked bolts adjustable endwise through certain of the openings, and nuts applied to the bolts and bearing against the back of the post.

40

2. A fence-post formed of plate metal which is bent longitudinally to form an angle-post, the bottoms of the sides of the post being bent at substantially right angles thereto and overlapped to form an anchoring-base, the longitudinal edges of the post being provided with alined angle-notches, the back of the post being provided with perforations alined between the notches, and fence-fas- 45 teners adjustable endwise through the perforations.

45

3. A fence-post blank provided in its longitudinal edges with transversely-alined wire-receiving notches, there being a longitudinal series of perforations formed through the 55 middle of the blank and located between the notches, one end of the blank being provided with a central longitudinal slit dividing said end of the blank into wings, said wings being provided with perforations disposed to come 60 into alinement when the blank is folded longitudinally to form an angle-post with the wings overlapped.

55

In testimony that I claim the foregoing as my own I have hereto affixed my signature in 65 the presence of two witnesses.

JOHN W. BARNES.
